UNITED STATES PATENT OFFICE.

LEONARD G. GRAY, OF DECATUR, ILLINOIS, ASSIGNOR TO WALRUS MANUFACTURING COMPANY, OF DECATUR, ILLINOIS, A CORPORATION OF ILLINOIS.

REFRIGERATOR DISPLAY-CASE.

1,387,486.

Specification of Letters Patent. Patented Aug. 16, 1921.

Application filed May 1, 1918. Serial No. 231,807.

To all whom it may concern:

Be it known that I, LEONARD G. GRAY, a citizen of the United States, residing at Decatur, in the county of Macon and State 5 of Illinois, have invented a certain new and useful Improvement in Refrigerator Display-Cases, of which the following is a specification.

My invention relates to that class of refrigerators, which are designed to provide means for attractively displaying fish, meats, fruits, vegetables, flowers, candy and any class of goods which it is desirable to keep cool and protected from dirt, dust and 10 flies.

My invention has for its object to provide a device which will provide a circulation which will prevent condensation.

Nearly all refrigerator show cases require 20 glass on the front or ends of the case to be in double or triple thicknesses, in order to prevent and retard the conduction of heat and cold.

In devices of this class, with which I am 25 familiar, the glass is usually set in permanently, and in time, the glass becomes murky, and inasmuch as there is no means of gaining access to the space intermediate the different sheets of glass the effect produced 30 by the display of the contents is greatly lessened.

One of the objects of my invention is to provide means whereby the double plates of glass, located in the front of my refrigerator 35 display case, are set in a pivoted frame which unlocks and swings outwardly enough to enable one to clean both plates of glass on both sides.

Another feature of my invention is that 40 by providing tanks for holding cracked ice which may be salted in hot weather any temperature from the normal atmospheric temperature of the street, down to forty-five degrees, may be obtained.

The tanks are formed of corrugated steel, 45 thus affording a cooling surface of one and three-fourths times the actual dimension of the tank, which enables me to attain the low temperature above mentioned.

By suspending the tanks from the top of 50 the case the cold air is caused to fall and thus a perfect circulation is attained which prevents condensation.

My means of accomplishing the foregoing 55 objects may be more readily ascertained by

having reference to the accompanying drawings, which are hereunto annexed and are a part of this specification, in which:

Figure 1 is an isometric perspective view of my improved refrigerator display case. 60

Fig. 2 shows the means to permit cleaning the glass plates.

Fig. 3 is a fragmentary detail view in perspective showing the interior construction.

Similar reference numerals refer to similar parts throughout the entire description. 65

As shown in the drawings, the case 1 is provided with tanks 2, one being located in each end of the case. The case is provided with a heavy glass top 3, and the front is 70 formed of two plates of glass, 4 and 5, the outer one of which is set in a frame 6, which is hinged or pivoted as at 7, the frame 6, being securely held in position by means of locks 8. This frame, which holds the outer 75 plate of glass 5, is constructed to fit directly against a packing formed by a felt strip which is invisible from the exterior of the case, and which will make a tight joint and prevent the cold air from escaping; the inner glass 4 is rigidly secured to the case 80 wall; the outer plate of glass is movable which affords a convenient means of cleaning the same.

The wooden walls 9, the bottom 10, and 85 the doors of the case are provided preferably with cork insulation although any other desired means employed for this purpose may be used.

The case is mounted upon cast iron legs 90 11, so as to provide a sanitary base. In the preferred construction of the doors, they do not extend to the bottom of the case, but terminate a short distance above the floor on the inside of the case, thus preventing 95 cold air dropping out when the door is opened.

At each end of the case 1, is provided a tank 2, which, as clearly shown in Fig. 3, is formed with corrugated sides which 100 greatly increase the cooling surface. The tank 2, is suspended from brackets 13, which are placed directly under the lift doors 14. In practice, I have found it desirable to have the tanks 2, extend within two inches of the 105 top of a metal drawer 15, which is adapted to hold milk or other bottled goods, the drawers being provided with automatic locks 16, which hold the drawers tightly closed preventing the leakage of cold air. This 110

construction permits the drawer to be withdrawn without the necessity of opening the door while the automatic locking feature enables a person to open the drawer with 5 one hand and to close and lock it in the same way. These drawers are concealed from the customer's view by shields 21, which are perforated to permit the cold air to circulate.

Between the bottom of the tank 2, and 10 the top of the drawer 15, is a pan 18, which is provided to catch any condensation and carry it off through an automatic drainage outlet 19, which is provided with a sealed air trap 20, thus preventing the loss of cold 15 air through the drainage outlet.

It will be apparent from the foregoing description that when it is necessary or desirable to clean the glasses 4 and 5 in the front of the case 1, the locks 8 are opened and the 20 frame 6 is swung outwardly upon its hinges 7, into the position clearly shown in Fig. 2, when access can be easily and quickly obtained to both sides of the glass, so that it can be kept clean and bright.

25 Having described my invention what I regard as new and desire to secure by Letters Patent of the United States is:

1. In a device of the character described,

the combination with a refrigerator display case, having a glass front and top, and a 30 plurality of ice containers therein, of a plurality of food containers located beneath said ice containers, with a perforated shield located adjacent the said food containers and which shields the contents therein from 35 observation through said glass front.

2. In a refrigerator display case having a portion of the top wall made of glass, a front wall containing an inner and outer piece of glass, the inner glass of which is 40 fixed, a frame which carries the outer glass, hinges which secure said frame to the case, a plurality of locks to lock said frame in a closed position for the purpose set forth.

3. In a refrigerator display case, having a 45 portion of the top wall made of glass, a front wall containing an inner and outer piece of glass, of a frame in which the outer plate of glass is mounted, said frame being hingedly secured to the case, a strip of felt 50 around the edge of said frame, and means to lock said frame tightly against said packing.

In testimony whereof, I have signed the foregoing specification.

LEONARD G. GRAY.
